B. ROSS.

SHANK PIECE FOR SHOES.

APPLICATION FILED AUG. 12, 1921.

Patented Sept. 26, 1922.

Inventor

Benjamin Ross
By his Attorney

H. T. Criswell

UNITED STATES PATENT OFFICE.

BENJAMIN ROSS, OF BROOKLYN, NEW YORK.

SHANK PIECE FOR SHOES.

Application filed August 12, 1921. Serial No. 491,726.

To all whom it may concern:

Be it known that I, BENJAMIN Ross, a citizen of the United States, and a resident of New York, borough of Brooklyn, in the 5 county of Kings and State of New York, having invented certain new and useful Improvements in a Shank Piece for Shoes, of which the following is a full, clear, and exact specification.

10 This invention relates to a class of devices adapted to be used in conjunction with footwear.

My invention has for its object primarily to provide a device or shank piece designed 15 to be employed in the shoe or boot of a person for stiffening the shank of the shoe as well as serving to support the arch of the foot of the wearer in a manner so that when under pressure the device will yield lengthwise as well as being capable of moving crosswise of the shoe, in order to afford comfort to the wearer when standing or walking. This is accomplished mainly by providing a bearing plate and a curved yielding 20 strip having one of its ends pivoted to the bearing plate so that when the plate and strip are secured on the shank of the sole interiorly of the shoe the pivoted part of the strip may slidably move lengthwise and 25 also move crosswise of the shoe when under pressure, in order that the arch of the foot of the wearer may be cushioned against downward as well as against lateral strain.

A further object of the invention is to provide 30 a shank piece of a simple, efficient and durable construction which may be made in any appropriate size of suitable material.

With these and other objects in view, the invention will be hereinafter more fully described with reference to the accompanying drawing forming a part of this specification in which similar characters of reference indicate corresponding parts in all the views, and will then be pointed out in the 40 claims at the end of the description.

In the drawing; Figure 1 is a top plan of one form of shank piece embodying my invention.

Fig. 2 is a side elevation of the shank 45 piece, and

Fig. 3 is a detail sectional view taken through a shoe with the device applied thereto, the latter also being shown in section.

55 The device or shank piece has a bearing

member or plate 10 and a yielding strip member 11. The bearing plate 10 may be of any suitable form, though the plate shown is substantially rectangular in shape. This bearing plate may be bent transversely in 60 a downward direction intermediate of its ends to provide a flat portion, as 12, in the center of which may be one or more holes 13, and the other end portion of the plate is curved somewhat upwardly, as at 14, in 65 a convexed or inverted concaved fashion so that this curved part is on a slightly higher longitudinal plane than the plane of the flat end portion 12 of the plate. The downwardly bent part of the plate provides 70 a shoulder or stop 14^a, while the intersection of the lower part of this shoulder with the concaved part 14 provides a transverse groove 14^b. When the device is applied interiorly of a shoe, as 15, or other type of 75 footwear the bearing plate 10 is fastened by a nail or bolt 16 which is driven through the hole 13 of the plate so that the curved or convexed part 14 of the plate protrudes toward the shank, as 17, of the shoe. The 80 free end of this curved part may then bear upon the heel or rear part of the shank of the shoe or may be slightly spaced from the heel, in order to yield somewhat when under pressure.

The strip 11 is preferably made of spring metal, and this strip has a flat right-angled end portion, as 18, of a width similar to the width of curved part 14 of the bearing plate 10. The other end portion may be 90 slightly curved in a lateral direction, as at 19, while this curved portion 19 may terminate with a somewhat tapered free end, as 20. This strip is curved lengthwise in a slightly inverted concaved form, while on 95 the edge part of the strip opposite to the central portion of its lateral curved edge may be a downwardly disposed concaved part, or socket, as 21.

The right-angled portion 18 of the yielding strip 11 is movably disposed on the central part of the convexed protruding portion 14 of the plate 10 so that the strip has a free bearing surface, and in the portion 18 of the strip is a slot 22 arranged lengthwise of the strip. The yielding strip 11 is pivoted to the free end portion of the concaved part 14 of the bearing plate 10 by a bolt or pin, as 23, which has a head of greater diameter than the width of the slot 110

22 of the strip 11, while the shank of the bolt is of a size to allow the slotted end of the strip 11 to freely move lengthwise back and forth on the bearing plate toward and 5 from the stop 14^a and into and out of the groove 14^b as well as permitting a pivotal movement crosswise of the bearing plate. The strip 11 is of a length so that when applied in the shoe its tapered end part 20 will 10 bear upon the sole of the shoe at the intersection of the shank 17 with the forward part of the sole so that the strip will span the shank part of the sole, and so that the slotted end of the strip will be spaced from 15 the stop 14^a for being movable into and out of the groove 14^b. The strip is fastened to the shoe by driving a nail or bolt 24 through a hole 25 provided in the tapered end portion 20 of the strip. The concaved part or 20 socket 21 is positioned for serving to support the metatarsal bone of the foot. In practice the slotted end of the strip 11 will yield sufficiently in upward and downward direction under the pressure of the wearer of 25 the shoe, and by providing for the pivotal sidewise movement of the strip the wearer will be afforded ease and comfort by the use of the device. Moreover, by providing the groove 14^b in the bearing plate 10 the 30 slotted end 18 of the strip will be adapted to freely move without tending to cut or damage the insole, as 26, of the shoe.

In the foregoing description, I have embodied the preferred form of my invention, 35 but I do not wish to be understood as limiting myself thereto, as I am aware that modifications may be made therein without departing from the principle or sacrificing any of the advantages of this invention, 40 therefore, I reserve to myself the right to make such changes as fairly fall within the scope thereof.

Having thus described my invention, I claim as new and desire to secure by Letters 45 Patent:

1. A shank piece for shoes, comprising a bearing plate adapted to be secured upon the heel portion interiorly of the shoe and having a part to protrude toward the shank 50 of the shoe, a convexly curved yielding strip having one of its ends slidably pivoted to the protruding part of the bearing plate and its other end adapted to be held to the shank of the shoe to allow the pivoted end of the strip to slidably move lengthwise and move crosswise on top of the bearing plate, and the second end part of the strip having a laterally extending concaved portion.

2. A shank piece for shoes, comprising a

bearing plate adapted to be secured upon 60 the heel portion interiorly of the shoe and having an inverted concaved part to protrude toward the shank of the shoe, and a convexly curved yielding strip having a slotted end pivoted to the central part of the 65 convexity of the protruding part of the bearing plate to allow the pivoted end of the strip to slidably move lengthwise and move crosswise on top of the concaved part of the bearing plate, the second end of said 70 strip being adapted to extend over the shank of the shoe as well as being adapted to be pivotally held to the sole of the shoe and the second end having a laterally extending concaved portion.

3. A shank piece as characterized, comprising a bearing plate having a flat end portion and having an inverted concaved end portion whereby a transverse groove is provided in the plate between said end portions, 80 and a convexly curved yielding strip having a slotted end pivoted to the free end part of the inverted concaved end portion of the bearing plate for allowing the slotted end of the strip to move inwardly and outwardly 85 of the groove of the bearing plate.

4. A shank piece as characterized, comprising a bearing plate with a stop intermediate its ends and one end of the plate having an opening, and a convexly curved 90 yielding strip having a slotted end pivoted to the other end of the plate to allow of being moved under pressure toward and from the stop of said plate.

5. A shank piece as characterized, comprising a bearing plate with a transverse groove intermediate its ends and one end of the plate having an opening, and a convexly curved yielding strip having a slotted end pivoted to the other end of the plate to allow of being moved under pressure inwardly 95 and outwardly of the groove of said plate.

6. A shank piece as characterized, comprising a bearing plate with a stop and an adjacent transverse groove intermediate its 105 ends and one end of the plate having an opening, and a convexly curved yielding strip having a slotted end pivoted to the other end of the plate to allow of being moved under pressure toward and from the stop and inwardly and outwardly of the 110 groove of said plate.

This specification signed and witnessed this 11th day of August A. D. 1921.

BENJAMIN ROSS.
